FREEZING CONTAINER

Armin O. Kuehmsted, Chicago, Ill.

Application November 19, 1934, Serial No. 753,590

10 Claims. (Cl. 62—108.5)

My invention relates to freezing containers for iceless refrigerating units and is concerned more particularly with devising containers of the individual type that may be easily removed from the freezing trays, tray or freezing coils and which are shaped and arranged to facilitate the extracting of the ice cubes.

One of the principal difficulties encountered with the use of domestic refrigerators of the ice-less type is the removal of ice cubes from the freezing trays, it usually being necessary to either expose the entire tray to running warm water in order to release the entire batch of cubes, or to a particular portion of the tray in order to release a few of the cubes. This operation is objectionable for a number of reasons, some of which are that a material portion of the ice cubes are melted, the operation is tedious and messy, and frequently the cubes are dropped on the floor or in the sink and generally rendered unfit for sanitary use.

It is, therefore, one object of my invention to devise an individual freezing container which is adapted for association with others of like construction in the freezing tray to make individual ice cubes, each of the containers being provided with lever means to facilitate its separate withdrawal from the tray.

A further object is to provide a container of the character indicated which is sized for insertion within a drinking glass, for example, whereby the ice cube may be loosened by the liquid in the glass and in which the lever means may be hooked over the rim of the glass to support the container during the loosening action and utilized to withdraw the container thereafter, thereby avoiding any touching of the liquid or the ice cubes by the hands.

A further object is to provide a container of the individual type in which one end wall is inclined or sloped to insure the slipping of the cube from the container when the latter is withdrawn from the glass or other receptacle.

These and further objects of my invention will be set forth in the following specification, reference being had to the accompanying drawings, and the novel means by which said objects are effectuated will be definitely pointed out in the claims.

50 In the drawings:

Figure 1 is a perspective view of a typical freezing tray showing the same filled with a number of my individual freezing containers and with one of the latter being removed therefrom.

Fig. 2 is a perspective view of one of the individual containers.

Fig. 3 is a sectional view of a drinking glass, for example, showing the ease with which one of my improved containers may be inserted therein and covered by the liquid that is to be chilled.

Fig. 4 is a view similar to Fig. 3, but showing the container being withdrawn from the glass and the loosened ice cube slipping therefrom.

Fig. 5 is a view similar to Fig. 3, but showing a taller glass and illustrating the use of the hooked handle, with which each of the containers is provided, as a means for supporting the container from the rim of the glass during the cube-loosening action.

15 Figs. 6 and 7 are perspective views of modified types of containers.

Referring to the drawings, the numeral 10 designates a shallow freezing tray or pan of a type that is commonly employed with domestic 20 refrigerating units and which may be utilized to support my individual containers during the freezing operation.

The individual container is illustrated in Fig. 2 and is denoted by the numeral 11. This container is preferably formed of metal, or of some other rigid material that does not exert a deleterious effect on the freezing rate. In general, it will be formed from sheet metal having a suitable thickness which may be pressed into the form substantially as illustrated, comprising side walls 12, a bottom wall 13, an end wall 14 and an inclined or sloping wall 15 for a purpose presently explained. The top of the container is open in order to receive the liquid to be frozen and the end wall 15 is so inclined that the area of the top is somewhat greater than the area of the bottom wall 13.

25 A handle or lever 16 is secured to the end wall 14, preferably by flattening one end of the lever as at 17 and soldering or otherwise securing the indicated end of the handle to the wall. This handle may be formed of a stiff wire or other material having a suitable gauge to resist bending under the action of loosening the container 30 from the bottom of the tray 10 as hereinafter described and the free end of the handle 16 is preferably hooked as at 18. Other handle constructions may be employed as desired. The handle 16 is extended away from the end wall 14 35 in slightly offset relation to the plane of the adjacent side wall 12. By so arranging the handle 16, it is possible to place the containers in the end-to-end relation as illustrated in Fig. 1, the handle of one container extending along the side 40 45 50 55

of the next container in line. In order to facilitate grasping of the handle when it is desired to remove a container from the tray, each handle is preferably inclined to, and extends somewhat above, the plane including the top of all the containers. Any adjustment of the height of the individual containers with respect to the depth of the tray 10 may be effected in order to insure that an adequate portion of each handle will be exposed for grasping and yet permit the insertion of the tray within the cooling unit of any standard type of domestic refrigerator.

In using my improved containers, the latter will be placed in the tray 10 after the general manner and arrangement indicated in Fig. 1, and each of the containers will then be filled with the liquid to be frozen. The tray, however, is merely a convenient holder for the containers and hence it is contemplated that the containers may be rested directly on the freezing plate or on a shelf within the freezing coil. After the freezing action has been completed, any one of the containers may be simply and easily removed from the tray, either while the tray is in the refrigerator or after removal therefrom, by grasping the hooked end 18 of the handle 16 and merely lifting upwardly. The leverage provided by the handle 16 is entirely adequate to break the frozen adherence of the container to the bottom of the tray 10, notwithstanding that some water may have collected in the bottom of the tray when the containers were first filled. It is contemplated, however, that the adherence of the individual containers to the bottom of the tray 10 might be somewhat lessened by suitably perforating the bottom of the tray.

After the containers have been individually removed as described above, the handle 16 provides a ready means for subsequently holding the container while the ice cube is being removed, either by the old method of holding the container under a faucet, for example, or by the method suggested in Figs. 3 to 5, inclusive. In this method, the container is inserted in a glass 19, or other receptacle, which contains the liquid to be chilled. The latter soon loosens the cube from the container, whereupon the latter may be withdrawn from the glass, as indicated in Fig. 4, the inclination of the end wall 15 facilitating the slippage of the cube from the container, even in as small a receptacle as a drinking glass. During this operation, it will be particularly noted that it is unnecessary to touch either the liquid to be chilled, or the ice cube, because the length of the handle 16 is such that these objectionable practices are avoided.

In Fig. 5 is shown a further use of the container, wherein the hooked end 18 of the handle is rested upon the rim of a deep glass 20. Thereafter, the action would be substantially as indicated in Fig. 4, but it will be particularly noted that the hooked end 18 insures that the sanitary characteristics of the container will be maintained, notwithstanding the depth of the receptacle containing the liquid that is to be chilled.

In Fig. 6 is illustrated a modified type of container represented numerically by the numeral 21, wherein the container itself possesses substantially the same shape as that illustrated in Fig. 2. The handle or lever 22, however, is formed specially and is preferably pivoted as at 23 on one of the side walls of the container. In the use of this type of handle, one arm 24 of the handle 22 is swung into the dotted position shown in Fig. 6 to thereby bear against the bottom of

the tray 10, for example, whereby the container 21 is loosened from the tray. A tab 25 may extend outwardly from the container to support the handle in the position shown during the freezing operation.

Referring to Fig. 7 there is illustrated a further modification in which one side wall 27 of the container 28 is provided with a socket 29, which may be formed, for example, by making the side wall with a tab which is subsequently rolled or curled to make the socket. The latter is provided with a bayonet slot 30 whose walls are intended to engage with a pin 31 on a convenient detachable handle 32. The handle is inserted in the socket with the pin in the slot and then turned to place the pin in the slot portion 33, thereby locking the indicated parts together and enabling the container to be lifted out of the freezing tray.

It will be understood that many changes may be made in the shape of the container without affecting the scope of the general conception set forth in this application and that the inclined end wall may be curved or otherwise shaped, provided that the general direction of this wall is such as to facilitate the slippage of the ice block in the manner indicated.

I claim:

1. The combination of a shallow freezing tray and a plurality of separate, open top, freezing containers resting on the bottom thereof, the tray and associated containers being adapted for insertion within the cooling unit of an iceless refrigerator, each of the containers having a handle secured thereto and adapted to be grasped to break the frozen adherence of the associated container to the tray by raising the handle, and each handle having a portion extending above the upper edges of an adjacent container to facilitate it being grasped.

2. The combination of a shallow freezing tray and a plurality of separate, open top, freezing containers resting on the bottom thereof, the tray and associated containers being adapted for insertion within the cooling unit of an iceless refrigerator, each of the containers having a handle extending in offset relation to one side thereof to permit close positioning of the containers in the tray and each handle having a portion extending above the upper edges of an adjacent container to facilitate the handle being grasped for breaking the frozen adherence of the associated container to the tray.

3. A freezing container of the individual type having enclosing side and end walls, a bottom and an open top, one of the end walls being inclined sufficiently to insure slippage of the ice cake therefrom when the container is immersed with its open top in a more or less vertical position in a receptacle containing the liquid to be chilled, and a handle for supporting the container during immersion whereby dipping of the fingers in the liquid is avoided.

4. A freezing container of the individual type adapted to be placed with other containers of like construction in the freezing compartment of an iceless refrigerator and having stiffened side, end and bottom walls and an open top for discharging the formed ice cake, and a substantially horizontally disposed handle secured thereto in offset relation to the plane of the top.

5. A freezing container of the individual type adapted to be placed with other containers of like construction in the freezing compartment of an iceless refrigerator and having stiffened side,

end and bottom walls and an open top for discharging the formed ice cake, and a substantially horizontally disposed handle secured thereto in offset relation to the plane of the top and to an adjacent side wall, respectively.

5. The combination of a shallow freezing tray and a plurality of separate, open top, freezing containers resting on the bottom thereof, the tray and associated containers being adapted for insertion within the cooling unit of an iceless refrigerator, each of the containers having a substantially horizontally disposed handle secured thereto in offset relation to the plane of the top thereof to permit close positioning of the containers in the tray and to facilitate the handle being grasped for breaking the frozen adherence of the associated container to the tray.

6. A freezing container of the individual type adapted to be placed with other containers of like construction in the freezing compartment of an iceless refrigerating unit and having rigid side, end and bottom walls and an open top for discharging the formed ice cake, and a handle projecting from one of the upstanding walls above the plane of the top and adapted to be grasped to break the frozen adherence of the container to the floor of the compartment by raising the handle.

7. A freezing container of the individual type adapted to be placed with other containers of like construction in the freezing compartment of an iceless refrigerating unit and having rigid side, end and bottom walls and an open top, and

a rigid handle secured to and projecting from the container in offset relation to a side wall thereof, the handle being adapted to be grasped to break the frozen adherence of the container to the floor of the compartment by raising the handle.

8. A freezing container of the individual type adapted to be placed with other containers of like construction in the freezing compartment of an iceless refrigerating unit and having rigid side, end and bottom walls, and a rigid handle projecting from one of the upstanding walls adapted to be grasped to break the frozen adherence of the container to the floor of the compartment by raising the handle, the free end of the handle being hooked to facilitate grasping by the fingers and to support the container on the lip of a receptacle into which the ice cake is to be discharged.

9. A freezing container of the individual type having enclosing side and end walls, a bottom and an open top having a greater area than the bottom, one of the end walls being inclined to the bottom and forming therewith a larger angle than the other end wall to thereby insure downward slippage of the ice cake from the container when the container is immersed in the liquid to be chilled and moved upwardly, the open top occupying a substantially vertical position and said inclined end pointing downwardly during discharge of the ice cake.
